UNITED STATES PATENT OFFICE.

LOUIS WERLÜN, OF ELSMERE, DELAWARE.

AUTOMATIC CHEMICAL FIRE-EXTINGUISHER.

SPECIFICATION forming part of Letters Patent No. 705,503, dated July 22, 1902.

Application filed January 20, 1902. Serial No. 90,413. (No model.)

To all whom it may concern:

Be it known that I, LOUIS WERLÜN, a citizen of the United States, and a resident of Elsmere, in the county of Newcastle and State of Delaware, have invented new and useful Improvements in Automatic Chemical Fire-Extinguishers, of which the following is a full, clear, and exact description.

My invention relates to automatic chemical fire-extinguishers, and more particularly of the type in which a liquid is precipitated from one receptacle into another for the purpose of generating a gas fatal to combustion.

Reference is to be had to the accompanying drawings, forming a part of this specification, in which similar characters of reference indicate corresponding parts in all the figures.

Figure 1 is a view of the fire-extinguisher, partly in section and partly in elevation. Fig. 2 is a fragmentary plan of the distributing-ring; and Fig. 3 is a fragmentary section of the fire-extinguisher, the inner casing being removed. Fig. 4 shows the alarm mechanism, consisting of an ordinary electric bell.

The flask or outer containing vessel 1 is provided with a permanent bottom 2 and with a detachable dome-shaped cover 3. Inside of this dome-shaped cover and concentric with the flask is a cylinder 4, detachably secured in position by means of bolts 5. An annular member 6, made in halves, secured together by means of bolts 7, encircles the upper portion of the flask 1, as shown more particularly in Fig. 2. The central portion 8 of this member has substantially the form of a semitube and is provided with perforations 9. Around the upper end of the flask and concentric thereto is a thin membrane 10 of annular form and made, preferably, of tin-foil or some similar substance which can easily be ruptured by means of pressure, against which membrane the annular member 6 bears. The upper portion of the flask is provided with a circle of holes 11, disposed centrally of the semitube and normally covered by the thin annular membrane 10.

The inner cylinder 4 is not quite long enough to reach the bottom of the flask and clears the same by a slight space 12. This leaves an annular space 13 between the inner surface of the flask and the inner cylinder. Suspended from the cover 3 is a basket 14,

which supports a cup 15, normally filled with a liquid 16, preferably an acid. A thin disk 18, of tin-foil or some similar substance easily 55 to be ruptured, rests upon the top of the cup 15 and is firmly secured thereto. Upon the annular mouth 17 of the cover 3 there rests the annular flange 19 of a funnel-shaped member 20, said flange being secured gas-tight upon the said annular mouth. An electrode 21 is fitted into this funnel-shaped member and is insulated therefrom by means of a cylindrical covering 22. To this electrode a wire 23 is connected. Another wire 24 is connected with the metallic neck 25 of the flask, and these two wires are connected with an electric alarm. (Not shown.) Within the metallic neck 25 are loosely placed a number of spherical bodies 26, such as shot. Upon 70 either side of said neck are disposed rods 27, slightly hooked at their lower ends, as shown, for the purpose of tentatively supporting the doors 28, which support the spherical bodies 26. These doors are pivoted at 29 and are 75 adapted to swing downward, as indicated by dotted lines in Fig. 1, and to engage the electrode 21.

In the neck 25 are receptacles 30 31, containing wax or some similar material which 80 is readily fused and in which the rods 27 are embedded. So long as the wax or similar substance does not melt, these rods support the doors 28, and consequently support the load of the bodies 26. When, however, the 85 wax melts, the rods 27 descend slightly and release the doors, thus establishing electrical communication between the wires 23 and 24, completing the circuit and actuating the alarm-bell B. In doing this the shot is precipitated upon the disk 18, rupturing the same instantly and filling the cup 15. The result is the acid 16 contained in the cup is precipitated into the body of the flask, where it unites with the alkali 34 in the flask and 90 causes a gas to be generated. The neck of the flask being provided with screw-threads 32 and with a gas-tight stopper 33 effectually prevents the escape of the gas thus generated. The result is that the pressure of the gas 100 upon the top of the liquid 34 forces the liquid inside of the inner cylinder downward and causes the liquid of the annular space 13 to rise, pass through the holes 11, and be

sprayed out through the perforations 9, thus extinguishing the fire. The inner cylinder 4 is removable, however, as indicated in Fig. 3. If the inner cylinder is removed, the action is slightly different. In this case the gas does not cause the liquid to rise, but instead the gas itself passes through the holes 11 and out of the perforations 9.

The operation of my device will be readily understood in view of the foregoing explanation. The vessel as a whole is placed in some part of the house to be protected from fire and located at a point near the ceiling where it will be comparatively inaccessible. If now a fire breaks out in the vicinity of the vessel, the wax members 30 and 31 will melt and the fire is extinguished, as above described, the electric alarm being actuated at the same time. The device is therefore automatic. It will be observed, therefore, that I have invented a simple and convenient device, not liable to get out of order, and which can be manipulated by any person of ordinary intelligence. It can be constructed at a nominal cost and is highly efficient for the purpose intended.

Having thus described my invention, I claim as new and desire to secure by Letters Patent—

- 30 1. An automatic chemical fire-extinguisher, comprising separate receptacles for holding liquids to be used in generating a gas fatal to combustion, a substance tentatively held adjacent to one of said receptacles, heat-controlled mechanism for precipitating said substance into said receptacle adjacent thereto for the purpose of displacing the liquid into either receptacle, and means for distributing the gas thus formed.
- 35 2. An automatic chemical fire-extinguisher, comprising separate receptacles for holding liquids to be used in generating a gas fatal to combustion, a substance tentatively held adjacent to one of said receptacles, heat-controlled mechanism for simultaneously actuating an electric alarm and precipitating said substance into said receptacle adjacent thereto for the purpose of displacing liquid into either receptacle, and means for distributing the gas thus generated.
- 40 3. An automatic chemical fire-extinguisher, comprising separate receptacles for holding liquids to be used in generating a gas fatal to combustion, a receptacle for tentatively holding a material for displacing one of said liquids and provided with movable doors for
- 45

- 55

supporting said substance, and a heat-controlled mechanism for automatically controlling said doors for the purpose of precipitating said substance.

4. An automatic chemical fire-extinguisher, comprising separate receptacles for holding liquids to be used in generating a gas fatal to combustion, a receptacle for tentatively holding a material for displacing one of said liquids and provided with movable doors for supporting said substance, said doors being capable of conducting an electrical current, electrical contacts to be engaged by said doors for the purpose of actuating an electric alarm, and a heat-controlled mechanism for automatically controlling said doors.

5. An automatic chemical fire-extinguisher, comprising separate receptacles for holding liquids to be used in generating a gas fatal to combustion, a receptacle for holding a material for displacing one of said liquids and provided with swinging members for tentatively supporting said substance, rods provided with hooks for normally supporting said doors, and bodies of fusible material for normally supporting said rods.

6. An automatic chemical fire-extinguisher, comprising separate receptacles for holding liquids to be used in generating a gas fatal to combustion, a receptacle for holding a material for displacing one of said liquids and provided with swinging members for tentatively supporting said substance, said members having electrical conductors, electrical contacts to be engaged by said members for the purpose of actuating an electric alarm, rods provided with hooks for normally supporting said doors, and bodies of fusible material for normally supporting said rods.

7. An automatic chemical fire-extinguisher, comprising a flask provided with a circle of holes, an annular member encircling said flask adjacent to said holes and provided with perforations, said holes and perforations being for the purpose of distributing an agent used in extinguishing fires, and means for automatically forcing said agent through said holes and said perforations.

In testimony whereof I have signed my name to this specification in the presence of two subscribing witnesses.

LOUIS WERLÜN.
